COMBINATION SALT AND PEPPER SHAKER

Filed Sept. 15, 1930

INVENTOR
Edward E. Harris.

UNITED STATES PATENT OFFICE

EDWARD E. HARRIS, OF TULSA, OKLAHOMA

COMBINATION SALT AND PEPPER SHAKER

Application filed September 15, 1930. Serial No. 481,967.

My invention relates to shakers and more particularly to combination salt and pepper shakers; and the object is to provide shakers which are particularly adapted for use in traveling in automobiles or other vehicles and for use in fishing and hunting parties and army services and which can be carried in kits and lunch boxes and the like. One advantage is that salt and pepper can be carried 10 and kept dry and ready for use and only one device is necessary for both salt and pepper. Other objects and advantages will be fully explained in the following description and the invention will be more particularly 15 pointed out in the claims.

Reference is had to the accompanying drawings which form a part of this application.

Fig. 1 is a side elevation of the shaker 20 assembled.

Fig. 2 is a vertical section of the same.

Fig. 3 is a plan view of the inner cap.

Fig. 4 is a plan view of the shaker.

Fig. 5 is a side elevation of the inner cap 25 partly in section.

Similar characters of reference are used to indicate the same parts throughout the several views.

This shaker has a body 1 which is hollow 30 and preferably cylindrical. The body 1 is divided vertically, a partition 2 for one compartment for salt and another compartment for pepper. The partition has a flange formed entirely about the all four edges.

One advantage of this construction is that 35 the flange will conform itself to the wall of the inner cover 3 at the top and conform to the socket 4 in the bottom of the shaker. The flange on the partition strengthens the

partition. The shaker is provided with an 40 inner cap 3 which has a flange formed on the edge and this flange projects downwardly within the body 1 and rests on an annular shoulder 5. The cap 3 has cut-outs or slots

45 6 in the skirt of the cap for receiving the upper edge of the partition 2 for holding the partition in place. The partition is thus held in place both at the top and at the bottom. The shaker is provided with an outer cap 7.

50 A groove is formed in the outer face of the

body near the top and a bead 8 is formed on the upper edge. The outer cap 7 is secured to the body by crimping the edge of the cap about the head 8.

The cap 3 has two openings 9 and 10 for 55 use in filling and discharging salt and pepper. The cap 7 has one opening 11 for filling and discharging purposes and has a plurality of perforations 12 for discharging salt and pepper. The outer cap 7 is rotatable on the 60 bead 8. The inner cap 3 is non-rotatable on account of the partition 2 which is held against rotation by its projection into the socket 4 in the bottom of the body 1 and the 65 grooves 13 in the vertical walls of the body 1. All the openings into the body or the compartments thereof may be closed at the same time simply by rotating the outer cap on the bead 8 until the outer cap comes to the 70 position shown in Fig. 4. The openings 9 and 10 are shown in dotted outline in Fig. 4. Neither the opening 11 nor the perforations 12 register with the openings 9 or 10. The cap 7 may be rotated to bring the opening 11 to register with the opening 9 of the inner 75 cap to fill with salt and can be rotated to bring the opening 11 to register with the opening 10 to fill with pepper. For serving salt, the cap 7 can be rotated to bring the perforations 12 to register with the opening 9. For serving pepper, the cap 7 can be rotated 80 to make the perforations 12 register with the opening 10. The outer cap 7 is rotatable and non-detachable.

85 What I claim is,—

A combination salt and pepper shaker comprising a hollow body having vertical grooves in the vertical walls thereof at diametrically opposite points and a socket groove in the 90 bottom, a partition vertically disposed in said body and occupying said grooves, an inner cap having a skirt projected within said body and having cut-outs in said skirt to receive the upper corners of said partition 95 and having openings for receiving and discharging salt and pepper and said cap being non-rotatable, and an outer cap rotatably and non-detachably mounted on said body and having an opening adapted to register 100

with either one of the openings in said inner cap and having a plurality of perforations adapted to register with either one of the openings in said inner cap and said outer cap being adapted to close both of said openings in the inner cap.

In testimony whereof, I set my hand, this
12th day of September, 1930.

EDWARD E. HARRIS.
